DESIGN FOR A PORTABLE WARDROBE CASE

Siegfried Meyer, New York, N. Y.

Application March 8, 1941, Serial No. 99,442

Term of patent 14 years

To all whom it may concern:

Be it known that I, Siegfried Meyer, a citizen of the German Reich and residing at New York, county of New York, State of New York, have invented a new, original, and ornamental Design for a Portable Wardrobe Case, of which the following is a specification, reference being made to the accompanying drawing, forming a part thereof.

Fig. 1 of the drawing is a perspective view of a portable wardrobe case in closed position and showing my new design.

Fig. 2 is a similar view of the case in opened position.

Fig. 3 is a rear elevational view thereof on a slightly smaller scale.

I claim:

The ornamental design for a portable wardrobe case, substantially as shown.

SIEGFRIED MEYER.
